UNITED STATES PATENT OFFICE.

EDWARD KRAFT, OF MADERA, PENNSYLVANIA.

WINDOW.

SPECIFICATION forming part of Letters Patent No. 703,600, dated July 1, 1902.

Application filed October 24, 1901. Serial No. 79,852. (No model.)

To all whom it may concern:

Be it known that I, EDWARD KRAFT, a citizen of the United States, residing at Madera, in the county of Clearfield and State of Pennsylvania, have invented a new and useful 5 Window, of which the following is a specification.

The invention relates to improvements in windows.

10 The object of the present invention is to improve the construction of windows, more especially the construction of the sashes and the manner of mounting the same, and to provide a simple and efficient window capable 15 of positively excluding wind and moisture and of confining the heat within an apartment.

16 The invention consists in the construction and novel combination and arrangement of 20 parts hereinafter fully described, illustrated in the accompanying drawings, and pointed out in the claims hereto appended.

25 In the drawings, Figure 1 is a vertical sectional view of a window constructed in accordance with this invention. Fig. 2 is a horizontal sectional view of a portion of the window, illustrating the construction of a metallic window-strip. Fig. 3 is a similar view 30 illustrating the construction of a wooden window-strip. Fig. 4 is a detail vertical sectional view of a portion of the metallic window-strip.

Like numerals of reference designate corresponding parts in all the figures of the drawings.

35 1 designates a window-frame provided with upper and lower sashes arranged in pairs, the sashes or members of each pair being guided on an expansible window-strip 2, which forms a guide for the sashes. The upper sashes 3 and 4 are arranged at the outside of the window-frame and are connected by screws 5 or other suitable fastening devices, the inner sash or member of the upper set being interposed 40 between a parting-strip 6 and the outer window-strip 2, and the outer member 3 being provided with extensions or flanges 7, which are arranged at the outer faces of the outer window-strips. The lower sashes 8 and 9 are connected by screws 10 or other suitable 45 fastening devices, the inner sash of the lower set being interposed between the inner

window-strips, as clearly shown in Fig. 3, and the outer sash of the lower set being extended beyond the side edges of the inner sash and arranged between the said parting-strips 55 6 and the inner window-strips. By arranging the sashes in pairs, as shown, dead-air spaces are provided between the members of each pair, which serve as non-conductors of heat and which operate to retain the heat within 60 an apartment. The arrangement of the sashes also permits the sashes or members 3 and 8 to be readily detached in summer, if desired, without affecting the operation of the expansible window-strips hereinafter described. 65

Each of the window-strips 2 is composed of an outer fixed section or member 11 and an inner movable section or member 12, which is held in engagement with the adjacent sash by coiled springs 13, disposed horizontally 70 and having their ends fitted in suitable sockets 14. The sections 11 and 12 are angular in cross-section, and the sockets are preferably tubular, as clearly shown in Fig. 2. The inner engaging section 12 is connected with the 75 fixed section by bolts 15 and is supported by means of arms or flanges 17 and 18, extending horizontally from the sections and overlapping each other, as clearly shown in Fig. 4. The bolts, which are disposed horizontally, limit the movement of the section 12 and are adapted to be adjusted to secure the desired frictional engagement between the section 12 and the adjacent sash. By this construction the sashes may be made to slide 80 freely, and the yielding expansible weather or window strips obviate the necessity of employing weights or other means for balancing the sashes and prevent the sashes from rattling and effectively exclude air and moisture. The fixed section 11 is provided with an attachment-flange 19, which is perforated for the reception of suitable fastening devices for securing the said section 11 to the window-frame. 85

90 The expansible weather-strip or window-strip may be constructed of either wood or metal, and when constructed of wood the outer section 20 will be angular or L-shaped in cross-section, and the inner section 21 will 95 preferably be solid, as shown in Fig. 3. The sockets for the spring 22 are formed in the

sections 20 and 21 of the wooden window-strip, and suitable bolts 23 are provided for connecting the sections to limit the movement of the section 21.

5 It will be seen that the window is simple and comparatively inexpensive in construction, that the yielding window-strips exclude air and moisture and at the same time prevent the sashes from rattling, and that sash-weights and other sash-balances are dispensed with. It will also be apparent that the sashes 3 and 9 are adapted to be readily detached in summer, if desired, and that the removal of these sashes will not affect the operation of 15 the expansible weather-strips.

The exterior of the window-frame and the sashes may be protected by a coating of waterproof paint or any other suitable material.

Changes in the form, proportion, size, and 20 the minor details of construction within the scope of the appended claims may be resorted to without departing from the spirit or sacrificing any of the advantages of this invention.

What I claim is—

25 1. In a window, the combination of a frame having a parting-strip, the upper and lower sashes arranged in pairs, the outer member of each pair being narrower than the inner member, and the outer member of the upper 30 pair being provided with lateral extensions or flanges, and the window-strips interposed between the side edges of the narrow sashes and the window-frame and composed of fixed sections secured to the window-frame, and 35 movable sections yieldingly engaging the

other members of the sashes, substantially as described.

2. In a window, the combination of a frame, a sash, and a window-strip composed of fixed and movable sections provided with sockets, 40 coiled springs disposed horizontally and fitted in the sockets and interposed between the sections, and an adjustable device for limiting the separation of the sections for varying the pressure on the sash, substantially as de- 45 scribed.

3. In a window, the combination of a frame, a sash, a window-strip composed of fixed and movable sections angular in cross-section provided with tubular sockets and having overlapping supporting-arms, springs fitted in the sockets, and means for limiting the movement of the movable section, substantially as de- 50 scribed.

4. In a window, the combination of a window-frame provided with parting-strips, expansible window-strips located at opposite sides of the parting-strips, and the upper and lower sashes arranged in pairs, the outer sash of the upper pair being provided with laterally-extending flanges arranged on the outer faces of the adjacent window-strips, substantially as described. 55

In testimony that I claim the foregoing as my own I have hereto affixed my signature in 60 the presence of two witnesses.

EDWARD KRAFT.
